GEAR POWER TAKE-OFF DRIVE FOR HAMMER MILLS

Albert H. Bottorff, St. Joseph, Mo.

Application April 21, 1950, Serial No. 157,275

3 Claims. (Cl. 74—15.6)

My invention relates to improvements in a gear power take-off drive for hammer mills or similar devices.

My invention relates more particularly to a gear power take-off drive for hammer mills of the type capable of being easily and quickly attached as a unit to certain standard types of hammer mills to permit a drive through a flexible shaft or universal joint from a tractor or similar power unit.

Hammer mills, as is generally known in the art, are used extensively in the agricultural sections of the country for grinding and cutting feed for cattle or other farm animals, and performing grinding and cutting operations upon various animal foods such as stalk corn, roughage or hay, and pulverizing granular foods such as ear corn, oats or other grains.

The usual hammer mill of this type includes a rotor upon which knives, hammers and other lacerating or chopping tools are positioned, the rotor normally being encased in a housing with a drive shaft extending therefrom, the drive shaft having a pulley keyed thereto so that the unit may be suitably driven from a source of power by means of a belt. Other types of drives at present on the market include V-belts or chain drives, none of which have proven entirely satisfactory for the following reasons:

Under a heavy strain the ordinary flat belt will frequently slip, causing loss of power and decreasing the efficiency of the hammer mill. V-belts or chain drives have a tendency to slip or stretch and belt tighteners or other adjusting means are required in the assembly, thereby entailing more expensive and complicated construction which can very easily become broken or out of order.

The principal object of the present invention is to provide a power take-off drive which overcomes any and all of the objections heretofore mentioned.

A further object of the invention is to provide an improved power take-off drive for hammer mills employing face gears capable of attachment to the side of the hammer mill in the normal position ordinarily occupied by the pulley usually furnished with hammer mills of the type described.

A further object of the invention is to provide a power take-off drive unit which includes a pinion and gear, a housing for the same and a bracket member connected to the housing so that the entire assembly may be handled as a unit and attached as a unit to the side of the hammer mill housing.

A further object of the invention is to provide a gear power take-off drive unit capable of easy attachment to or detachment from the side of the hammer mill housing, the unit having a driving gear and pinion sealed therein and efficiently lubricated so that once it is installed as a unit it will operate efficiently for a long period of time without becoming broken or out of order.

Other objects and advantages will become more apparent from the following description wherein reference is had to the accompanying drawings, upon which

2

Fig. 1 is a side elevational view illustrating the use of an ordinary farm tractor for providing power to operate a hammer mill, and includes the power take-off drive from the tractor, the gear power take-off unit which I provide, and the usual type of hammer mill to which the take-off unit is attached;

Fig. 2 is a generally front perspective view of a fragment of the side wall of the hammer mill showing the gear housing frame attached thereto with the gear housing cover raised thereabove to show the opening provided for inserting and assembling the gears and introducing lubricant thereto;

Fig. 3 is a fragmentary plan view showing a portion of the hammer mill housing and the gear take-off unit which I provide, the cover plate thereof being removed to more clearly show internal parts;

Fig. 4 is a side elevational view of the parts shown in Fig. 3;

Fig. 5 is a side elevational view of a modified form of power take-off drive and split housing therefor; and

Fig. 6 is a vertical sectional view of the same taken generally on the line 6—6 of Fig. 5.

In the preferred embodiment of the invention illustrated and described in the drawings, I show a typical installation of the gear power take-off drive 10 mounted as shown in Fig. 1 upon the side of the housing 12 of a hammer mill, the hammer mill including generally the feed table 14 upon which the grain is fed to the housing 12 in which a rotor having knives, hammers or other lacerating or chopping means is located. A discharge pipe 16 may extend upwardly therefrom through the dust collar 18 and discharge chute 20.

I prefer to provide a source of power for driving the hammer mill shown in the nature of a tractor 22 which has a power take-off shaft 24 that is connected by means of a universal joint 26 to the stub shaft 28 which extends into the gear power take-off drive unit 10.

As more clearly shown in Figs. 2, 3 and 4, a rotor R which is positioned in the housing 12 is mounted upon a drive shaft 30 which extends through the side wall 32 of the housing 12 and is normally received in a bearing 34 positioned upon an angle member 35 secured to the side wall 32 of the housing 12. The shaft 30 in the original installation extends beyond the bearing 34 and has a pulley keyed thereto, the pulley being held on the shaft in any suitable or desirable manner.

As hereinbefore pointed out it is desirable to provide a drive other than by means of a pulley and belt for the hammer mill. Accordingly, and in order to connect up a drive for the hammer mill with a tractor or other power unit, I remove the usual pulley which has been provided and mount a pinion gear 36 in driving relation on the shaft 30, the gear having a collar or spacer 38 to position the same within the gear housing 40 which is a part of the unitary drive means that I provide. The shaft 30 may be journalled in bearings 42 and 44 upon opposite walls 46 and 48 of the housing 40. As also seen in Fig. 2, a closure cap 49 may be employed if desired to completely enclose the end of the shaft 30.

The gear 36 is adapted to be meshed with a face gear 50, also positioned in the housing 40 and mounted upon the shaft 28 which is journalled in suitable bearings 52 and 54 connected to the side walls 46 and 48 of the housing 40. A suitable cap member 56 may be connected over the opening 58 in the top of the housing 40, being held in position by means of bolt members 60.

In order to firmly connect the gear housing 40 to the side of the hammer mill housing 12, I weld or otherwise rigidly connect an angle member 62 by means of one of its legs 64 to the side wall 46 of the housing 40, the base of the angle member being adapted to rest upon the brace 35 of the housing 12 and connected thereto by

means of bolt members 66. An additional brace member 68 may be bolted to the side wall 48 of the housing 40 and extend downwardly and be fastened to the side of the housing 12.

The housing 40 is adapted to contain a sufficient quantity of lubricant so that the gears 36 and 50 will be continuously running in an oil bath when in operation.

From the above and foregoing description it can be seen that I have provided a unitary assembly which can be connected to the shaft 30 and by means of a key 29 the shaft 28 is connected to a universal drive member 26 of a tractor power take-off shaft. The unit, including the housing 40, is easily and quickly bolted to the side of the hammer mill housing 12 and rigidly secured thereto by means of the angle member 62 and the brace 68.

In Fig. 5 and Fig. 6 I have shown a modified form of construction wherein the gear housing may consist of the similarly shaped housing members 41 and 43, the same having bolt flanges 70 extending therefrom to receive the bolt members 72 which securely connect the housing halves together. In this construction a gasket 74 is provided between the peripheral flanges of the two housing sections, the housing sections being adapted to be held as a unit against the side wall of the hammer mill housing 12 by means of the angle member 76 which is bolted upon the angle member 35 on the side of the housing 12.

The gear housing unit herein shown may have internally disposed roller bearings 78 and 80 to receive the shaft 30, oil seals 82 being provided at the openings 84 in the housings to prevent the escape of oil at these openings.

In a similar manner the stub shaft 28 which carries the gear 50 is mounted in suitable roller bearings 86 and 88, an oil seal 82 being provided at the opening 90 of the housing section 41 through which the stub shaft 28 extends.

With the construction shown in the modified form of the invention I provide a filling plug 81 in one of the housing sections to permit the introduction of lubricating oil to the gear members 36 and 50, and a drain plug 83 adjacent the lower end for removing the same when fresh oil is desired.

From the above description it can be seen that I have provided a comparatively simple unit which may be attached to the rotor shaft 30 of the hammer mill in a manner of minutes by farmers or other persons not unusually skilled as mechanics. The installation and attachment of the unit is a simple matter due to the construction which I have provided, the angle member 62 and the angle member 76 in the modified form of the invention being easily attached to the member 36 to position the unit against the side of the rotor housing of the hammer mill.

While I have illustrated one complete example of the physical embodiment of my invention according to the best mode which I have thus far devised, and a modifica-

tion thereof wherein split gear housings are employed, it will be understood that various changes and alterations may be made in the exemplified structure within the scope of the appended claims. What I desire to secure and

5 protect by Letters Patent of the United States is:

1. A power take-off drive for a hammer mill rotor shaft adapted to be attached as a unit to the side of the hammer mill rotor housing through which said shaft extends, said unit comprising a housing having a pinion and a face gear therein, said pinion attached to said rotor shaft, a stub shaft extending through one side of said housing, said face gear attached thereto, an angle iron member connected to the side of said housing for fastening the same to the side of said hammer mill housing and a bearing for said rotor shaft carried by said angle iron.

10 2. A power take-off drive for a hammer mill rotor shaft adapted to be attached as a unit to the side of the hammer mill rotor housing through which said shaft extends, said unit comprising a housing having a pinion and a face gear therein, said pinion attached to said rotor shaft, a stub shaft extending through one side of said housing, said face gear attached thereto, an angle iron member connected to the side of said housing for fastening the same to the side of said hammer mill housing, said housing having an open upper end and a cover member for closing the same, and a bearing for said rotor shaft carried by said angle iron.

15 3. A power take-off drive for a hammer mill rotor shaft adapted to be attached as a unit to the side of the hammer mill rotor housing through which said shaft extends, said unit comprising a housing having a pinion and a face gear therein, said pinion attached to said rotor shaft, a stub shaft extending through one side of said housing, said face gear attached thereto, an angle iron member connected to the side of said housing for fastening the same to the side of said hammer mill housing, said housing having an open upper end and a cover member for closing the same, said stub shaft having a universal drive connection therein, and a bearing for said rotor shaft carried by said angle iron.
